UNITED STATES PATENT OFFICE

EDWARD E. JOHNSON, OF ST. PAUL, MINNESOTA

DEEP-WELL PUMP

Application filed December 22, 1927. Serial No. 241,773.

My invention relates to deep well pumps, and more particularly to double stroke geared pumps having two pump rods for reciprocating two pump plungers in opposite directions toward and away from each other. The construction disclosed herein is in the nature of an improvement over my Patent No. 1,438,492 dated December 12, 1922. An object of the present invention is to provide an extremely rigid pump frame or casing in which the operating mechanism is compactly arranged in such manner that the height of the pump structure is reduced to about one-half of that formerly required. Another object is to provide planetary gear mechanism for operating the pump rods so arranged that the pump rods are offset from the center of the planetary gearing whereby the operating mechanism may be brought low down toward the base. Another object is to provide stuffing boxes which are positioned above instead of at the bottom of the oil reservoir so that the oil which circulates within the pump case can drain back readily and does not subject them to a static head of oil at any time. Another object is to provide for pumping the oil from the oil reservoir to the top of the frame or casing and to the planetary gearing from which places it flows back to the oil reservoir so that renewal of oil becomes necessary only at long intervals of time. Another object is to provide a pump frame or casing embodying easy means of connecting it with and disconnecting it from the pump rods whereby the latter may be readily withdrawn from the well whenever desired. Another object is to provide a substantial casing enclosing the operating mechanism so as to exclude dirt and which at the same time may be readily opened for inspection of the interior. Another object is to provide a casing completely enclosed so that no baffle is necessary to divert water leakage away from the planetary gearing and the crank mechanism.

The full objects and advantages of my invention will appear in connection with the detailed description thereof, and the novel features of my inventive idea will be particularly pointed out in the claims.

In the accompanying drawings which illustrate a practical embodiment of my invention,—

Fig. 1 is a front elevational view of the pump with the cover removed. Fig. 2 is a view in vertical section as viewed from the front on the line 2—2 of Fig. 3. Fig. 3 is a view in vertical section on the line 3—3 of Fig. 2. Fig. 4 is a top plan view of a cross head showing a provision for clearance between the same and a rod carrying member. Fig. 5 is a view in vertical section similar to Fig. 3 showing the pump frame moved back from operating position. Fig. 6 is a view in section on the line 6—6 of Fig. 8. Fig. 7 is a view in horizontal section on the line 7—7 of Fig. 2. Fig. 8 is a view in horizontal section on the line 8—8 of Fig. 1. Fig. 9 is a view in section on the line 9—9 of Fig. 8.

As shown in the drawings, I provide a base member 10 upon which the pump frame is adapted to be secured. The pump frame includes an oil reservoir at the bottom having a rear wall 12 extending up above the level of the oil which it is desired to maintain in the reservoir. The bottom of the reservoir toward the front thereof has an inclined portion 14 with a lug 16 provided where this inclined portion joins the horizontal portion of the bottom. The inclined portion 14 at its upper end merges into a vertical wall 18 which is concaved inwardly as shown in Fig. 7 for the purpose of providing clearance only as otherwise this wall might just as well be flat. The frame has two side members 20 and 22 which extend up further than the wall 18, these side members being rounded at their upper ends as will be understood from Fig. 3. The lower portions of side members 20 and 22 are provided with recessed portions in which internal ring gears 38 are seated against annular flanges 25 which annular flanges merge into vertical wall 18 to complete the oil reservoir in front. Annular flanges 25 are provided with clear openings 26 through which the operating mechanism reciprocates and which will be described later. Similar bull gear housings 24 are concentrically located on the frame by enclosing the extended outer rim of ring gears 38 and are bolted to side members

20 and 22 by annular flanges to complete the oil reservoir, and further as will be apparent from Fig. 9 each bull gear housing has an external bulged portion 29 closed outwardly by cap 140 to enclose and carry the drive shaft 28 and its bearings 133. Side portions 20 and 22 are further provided with clear openings 27 for the assembly and operation of drive shaft 28 which may be driven in any suitable manner as by means of a belt pulley 30 secured thereto. Also secured to the shaft 28 are two pinions 32 meshing with external spur gears 34, called bull gears, journalled on studs 36 secured centrally to the bull gear housings 24 by nuts 37. Internal ring gears 38 are rigidly secured in the frame, being concentrically positioned with each other and with the bull gears 34 and located between the latter and the flanges 25. Spur gears 40 mesh with the internal ring gears 38, these spur gears being one-half of the diameter of the internal gears. A crank pin 42 has crank members 44 at its two ends and these crank members carry outstanding stub shaft ends 46 which are journalled in the bull gears 34 between the centers and peripheries of the latter. The gears 40 are rigidly mounted on the crank members 44 adjacent the stub shaft ends 46 and are concentric therewith. The crank pin 42 has its axis in the pitch circles of the gears 40. In the operation of the gearing, the rotation of the bull gears 34 carries the gears 40 in an annular path, thereby rolling them around within the internal gears 38. Since the latter are twice the diameter of the gears 40, the crank pin 42 moves in the path of a diametral line of the internal gears 38 and vertically when as in the present instance, the crank pin and the stub shafts 46 are in a vertical plane at the end of the stroke. Journalled upon the crank pin 42 is a bearing member 48 of the vertical connecting rod 50. The connecting rod 50 at its upper end carries a pair for rollers 52 which engage the rear of guideways 54 formed or carried by the inner faces of the side members of the frame 20 and 22 and this connecting rod also at its upper end carries a pair of rollers 56 which engage the front of said guideways. These pairs of rollers take care of all horizontal components of thrusts tending to produce motion and cause the connecting rod 50 to travel straight up and down. Projecting out from the upper end of the connecting rod, there is a lug 58 to which an upwardly extending bolt 60 is adjustably secured by nuts 61. An equalizing bar 62 is provided with a central opening through which the bolt 60 passes loosely, the opening, however, being smaller than the head of the bolt so that the bar cannot be pulled free therefrom. Clevises 64 are pivotally attached to the ends of the bar 62 while ends of sprocket chains 66 are secured to these clevises. The sprocket chains 66 pass over sprocket wheels 68 which revolve on a shaft

70 mounted in the upper portion of the frame. It is obvious that sprockets 68 serve only to change the direction of the chains 66 and may be replaced by rolls for the same purpose. The other ends of the sprocket chains 66 are secured to a cross head 72 having a portion to which the upper ends of tie rods 74 are secured by nuts 76. The lower ends of the rods 74 are secured to a yoke 78 to which is secured the upper end of an outer hollow reciprocating pump rod 80 which slidably surrounds an inner solid reciprocating pump rod 82 whose upper end is secured by a nut 84 to a projection 86 carried by the upper end of the connecting rod 50. The purpose of the bar 62 is to distribute the load on pump rod 80 equally between chains 66 irrespective of slight changes in either due to wear, the chain adjustment being maintained by bolt 60. The rod 82 passes through a stuffing box 88 while the tie rods 74 pass through stuffing boxes 90, these stuffing boxes being carried by a bracket 92 whose lower portion is cylindrical to fit oil tight upon a concaved cylindrical seat 94 formed in the upper edge of the wall 18 as will be understood from Fig. 1, this upper edge being thickened to form a flange 96. The portion 93 of the stuffing box bracket 92 is in alignment with portions 19 of the pump frame as shown in Fig. 8 to form a continuous 95 abutment within which the lower edge of the sheet metal casing 146 is held to complete the closure of the pump frame so that oil falling on the casing 146 will drain by gravity onto stuffing box bracket 92 and from thence down partition 18 to the oil reservoir. The bracket 92 is removably held to its seat by screw bolts 98 for a purpose which will appear later. Retriever chains 100 are secured at one end to the outer end portions of the cross head 72 as shown in Fig. 1 while as shown in Fig. 5, these two retriever chains pass around sprocket wheels 102 carried by the frame and their other ends are secured to pins carried by the upper end of the connecting rod 50. In order to provide a simple and efficient means for pumping the oil in the oil reservoir for the purpose of supplying lubrication to the moving parts of the pump, the upper end of a downwardly extending plunger 104 is secured to the lug 58 carried at the upper end of the connecting rod 50, this plunger reciprocating in a cylinder 106 whose lower end is anchored to the lug 16 in the bottom of the oil reservoir. The cylinder 106 is provided with a coupling member 108 near its lower end and to this coupling member valve casings 110 and 112 are connected at opposite sides thereof as shown in Fig. 2. The valve casing 110 contains a check valve 114 which opens to admit oil into the cylinder when the plunger is moved upwardly. The valve casing 112 contains a check valve 116 which closes when the plunger is moved upwardly. For downward movement of the plunger, the

opening and closing of these two valves are, of course, reversed. The valve casing 112 has connected thereto a vertical pipe 118 to the upper end of which a horizontal pipe section 120 is connected. The outer end of the pipe section 120 is connected to a vertical pipe 122 which continues on to the top of the frame, the purpose of the offset pipe member 120 being to bring the pipe 122 close to one of the side walls of the frame. A horizontal pipe 124 leads from the upper end of the pipe 122 transversely of the frame. The pipe 124 is provided with spraying nozzles 126 for spraying oil upon the guideways and working parts at the top of the frame. From the upper part of the pipe member 118, branch pipes 128 and 130 lead into passages 132 as shown in Fig. 6 for lubricating the bearings of the driving shaft and the gearing. The oil after leaving the passages 132 finds its way by gravity to the inside lower portion of the bull gear housing 24 whence it is picked up by the bull gear in its rotation for lubrication thereof and then escapes through the ring gear 38 to fall back into the oil reservoir. Surplus oil traveling along shaft 28 is intercepted by oil groove 135 and returned to the inside of the bull gear housing through the passage 134. In order to provide a rigid construction for the frame or casing, a flat bar 136 extends between the side members of the frame near their upper ends as shown in Figs 2 and 3. For the same purpose, a curved bar 138 extends between the side members near the position occupied by the driving shaft 28 as shown in Figs. 4, 5, and 8. The bar 138 is in the form of a half cylinder which when the shaft 28 is in place has an eccentric position in relation thereto. This positioning permits the shaft 28 and the gears 32 to be introduced into place in the frame very readily. For this purpose, the holes 27 are large enough to permit passage of the pinions 32 and when the shaft 28 has been pushed into proper place it is permitted to drop so as to bring the teeth of the pinions 32 into mesh with the teeth of the gears 34. When the shaft 28 has been put in place, the bull gear housings 24 are closed by caps 140 which are bolted in place and which contain bearings 135 for the shaft. When the pump is in operating position, the frame is bolted to the base member 10, which it will be understood from Figs. 5 and 7 is longer than the portion of the frame which rests thereon. The rear portion of the base on its upper central portion is in the form of a rack having teeth 142. The lower end of the frame carries a perforated lug 144 so that by inserting a pry bar, the frame may be moved backwardly into the position shown in Fig. 5 when it is desired to obtain access to the well and pull the pump rods. By referring to Figs. 1, 3, and 5, it will be readily understood that the frame may be thus moved backwardly after first removing the nut 84 on

the upper end of the pump rod 82, the nuts 76 on the upper ends of the two tie rods 74 and the screw bolts 98, and turning the gearing sufficiently to free the rods from their sockets in the lug 86 and cross head 72 respectively. This may be done without disturbing the operative relation of the parts comprising the driving mechanism.

It will be noted from Fig. 3, that there is a slight space between the inside and outside pump rods which may be filled with grease which keeps the rods thoroughly lubricated for a long time, this grease being kept in place by a stuffing box 150 which is secured to the upper end of the outside rod and through which the inside rod passes. The stuffing box 150 serves also in the usual manner to prevent water leakage. By referring to Fig. 4, it will be seen that the head of the projection 86 carrying the upper end of the inner rod may readily pass the cross head 72 during the up and down strokes. By referring to Fig. 7, it will be understood that the inwardly concaved wall 18 provides clearance for the two pump rods, the yoke 78 and the tie rods 74 so that the pump rods after passing through the base 10 extend up between the space defined by the side walls of the frame as will be apparent from Fig. 3. By referring again to Fig. 7, it will be noted that sufficient clearance is also left for the up and down movement of the crank pin and the bearing member 48 journaled thereon. It will be seen from Fig. 3 that the bearing member 48 at the lower end of the stroke dips into the oil in the oil reservoir and that the wall 18 is in the nature of a partition in the lower portion of the pump casing or chamber and constitutes a confining wall for the oil reservoir.

The entire frame between side portions 20 and 22 above the stuffing box bracket 92 and rear wall 12 is open for the purposes of assembly and inspection in operation if desired and is normally closed by sheet metal cover members 146 and 148 which are adapted to fit inwardly projecting flanges 21 on the side portions 20 and 22 thus completing the enclosing of the operating mechanism positioned between the side portions of the frame against loss of lubricating oil from within or the entrance of foreign matter from without.

The operation and advantages of my invention have to a large extent been set forth. By means of the planetary gearing and the guide mechanism previously described in detail, the vertical connecting rod 50 is caused to reciprocate straight up and down. When this connecting rod makes its down stroke, the operating chains 66 connected therewith and passing around the sprocket wheels 68 cause the cross head 72 to move upwardly. By means of the tie rods 74 which connect the cross head 72 with the yoke 78 secured

to the upper end of the hollow pump rod 80, the latter is caused to move upwardly. At the same time, the solid inner pump rod 82 is caused to move downwardly since its upper end is secured to the projection 86 carried by the upper end of the connecting rod 50. When the connecting rod 50 makes its up stroke, the pump rod 82 is caused to move upwardly and the cross head 72 carrying with it the pump rod 80 is caused to move downwardly by the operation of the retriever chains 100 connected to said cross head at one end and connected at the other end to the upper end of the connecting rod 50 after having their direction changed by passing around the sprocket wheels 102. The construction and operation of the pumping mechanism has now been set forth with sufficient clearness to allow of a statement of the improved results secured thereby as compared with my former United States Patent No. 1,438,492 above referred to.

The present construction makes possible the following: to construct the pump frame with an oil reservoir in the lower portion not pierced by any operating mechanism, which avoids the necessity of maintaining stuffing boxes oil tight under a static head; to place the planetary motion and the vertical space required for the reciprocation of the outside rod yoke side by side instead of in axial alinement thus saving head room; to place the pump rod top ends for connection and reciprocation past each other within the same vertical portion of the pump frame so that the oil stuffing boxes on the rods are above the oil level maintained in the oil reservoir and that their only purpose is to free the rods of such oil as splashes on them, there being no static head of oil to resist; to submerge the lubricating oil pump in the oil reservoir with its plunger reciprocated by the pitman in order to provide flood lubrication of all moving parts; to provide ample openings for inspection of the pump in operation by the removal of the sheet metal plates; to provide extreme accessibility to the parts to be separated in moving the pump back to pull the rods from the well; to secure an extremely low center of gravity of the frame and operating parts which adds to their stability and freedom from vibration in operation.

I claim:

1. In a pump of the class described, a casting comprising two planetary gear mechanisms in spaced parallel relation, a crank pin connected thereto and reciprocable thereby, a plurality of pump rods in offset parallel relation thereto, and operating connections between said pump rods and crank pin whereby said pump rods are given motion alternately in opposite and opposed directions in a plane parallel to the plane of motion of said crank pin.

2. A pump casting comprising an oil reser-

voir in its lower portion, a detachable stuffing box bracket carried on one wall thereof above the level of said oil reservoir, a framework comprising two substantially parallel sides carried thereon, and a sheet metal cover attached thereto to complete the enclosure, substantially as and for the purpose specified.

3. A pump comprising a casing, planetary gear mechanism mounted therein, a crank pin connected to said planetary gear mechanism and reciprocable thereby in a straight line, a pump rod offset with relation to said gear mechanism, and operating connections between said crank pin and said pump rod for the reciprocation of the latter in a plane parallel to the plane of motion of said crank pin.

4. In a pump, the combination of a frame having seats therein, operating mechanism consisting of a shaft carrying pistons and mounted in said seats in spaced relation and across a median line of the frame in alinement with each other, said seats being provided with openings of sufficient size to permit assembly of said operating mechanism by end-wise sliding movement thereof, a pump rod, and connections between said operating mechanism and pump rod for reciprocating the latter.

5. A pump comprising a base, a casing mounted thereon, planetary gear mechanism in said casing, a crank pin connected to said planetary gear mechanism and reciprocable thereby in a straight line, a plurality of pump rods offset with relation to said gear mechanism, and operating connections between said crank pin and said pump rods for reciprocating the latter in a plane parallel to the plane of motion of said crank-pin.

6. A pump comprising a base, a casing mounted thereon, planetary gear mechanism in said casing, a crank pin connected to said planetary gear mechanism and reciprocable thereby in a straight line, two pump rods offset with relation to said gear mechanism, and operating connections between said crank pin and said pump rods for reciprocating the latter in opposite direction with relation to each other in a plane parallel to the plane of motion of said crank pin.

7. A pump comprising a base, a casing mounted thereon, planetary gear mechanism in said casing, a crank pin connected to said planetary gear mechanism and reciprocable thereby in a straight line, a connecting rod journaled at one end on said crank pin for reciprocation thereby, a projection extending laterally from said rod, a pump rod attached to said projection for reciprocating movement, a second pump rod, and operating connections between said connecting rod and said second pump rod for reciprocating the latter in opposite direction relatively to said first pump rod.

8. A pump comprising a base, a casing mounted thereon, planetary gear mechanism in said casing, a crank pin connected to said planetary gear mechanism and reciprocable thereby in a straight line, two pump rods offset with relation to said gear mechanism, one of said pump rods being connected with said crank pin in offset relation for reciprocating movement in the same direction there-
5 with, and connections between said crank pin and the other of said pump rods for reciprocating the latter in opposite direction relatively to said first pump rod in a plane parallel to the plane of motion of said crank
10 pin.
15 9. A pump comprising a base, a casing mounted thereon, planetary gear mechanism in said casing, a crank pin connected to said planetary gear mechanism and reciprocable thereby in a straight line, two pump rods offset with relation to said gear mechanism, one of said pump rods being connected with said crank pin in offset relation for reciprocating movement in the same direction there-
20 with, a cross head to which the other of said pump rods is connected, and connections be-
25 tween said crank pin and said cross head for reciprocating the latter in opposite direction relatively to said first pump rod in a plane parallel to the plane of motion of said crank
30 pin.
35 10. A pump comprising a base, a casing mounted thereon, planetary gear mechanism in said casing, a crank pin connected to said planetary gear mechanism and reciprocable thereby in a straight line, a connecting rod journaled at one end on said crank pin for reciprocation thereby, a projection extending laterally from said rod, a pump rod attached
40 to said projection for reciprocating movement, a second pump rod, a cross head to which said second pump rod is connected, operating chains connecting said connecting rod with one side of said cross head, and re-
45 triever chains connecting said connecting rod with the other side of said cross head.
50 11. A pump comprising a base, a casing mounted thereon, planetary gear mechanism in said casing, a crank pin connected to said planetary gear mechanism and reciprocable thereby in a straight line, a connecting rod journaled at one end on said crank pin for reciprocation thereby, guide ways carried by said casing for keeping the travel of said rod
55 in a straight line, a projection extending laterally from said rod, a pump rod attached to said projection for reciprocating movement, a second pump rod, and operating connections between said connecting rod and said
60 second pump rod for reciprocating the latter in opposite direction relatively to said first pump rod.
65 12. A pump comprising a base, a casing mounted thereon, planetary gear mechanism in said casing, a crank pin connected to said planetary gear mechanism and reciprocable thereby in a straight line, a connecting rod journaled at one end on said crank pin for reciprocation thereby, guideways carried by said casing, rollers carried by the outer end of said rod and engaging said guideways for keeping the travel of said rod in a straight line, a projection extending laterally from said rod, a pump rod attached to said projection for reciprocating movement, a cross head offset from said connecting rod, a second pump rod attached to said crosshead, laterally deflected operating chains connecting said connecting rod and one side of said cross head, and laterally deflected retriever chains connecting said connecting rod and the other side of said cross head, said operating and retriever chains being arranged to cause reciprocation of said second pump rod in opposite direction relatively to said first pump rod.

13. A pump comprising a base, a casing mounted thereon, planetary gear mechanism in said casing, a crank pin connected to said planetary gear mechanism and reciprocable thereby in a straight line, a plurality of pump rods offset with relation to said gear mechanism, operating connections between said crank pin and said pump rods for reciprocating the latter in a plane parallel to the plane of motion of said crank pin, an oil reservoir below said gear mechanism, and mechanism operated by said crank pin for delivering oil from said oil reservoir to said gear mechanism and connections.
14. A pump comprising a base, a casing mounted thereon, planetary gear mechanism in said casing, a crank pin connected to said planetary gear mechanism and reciprocable thereby in a straight line, a connecting rod journaled at its lower end on said crank pin, a plurality of pump rods offset with relation to said gear mechanism, operating connections between the upper end of said connecting rod and said pump rods for reciprocating the latter, an oil reservoir below said gear mechanism, a cylinder extending into said oil reservoir and fixed with relation thereto, a plunger attached to the upper end of said connecting rod and working in said cylinder, and pipe connections extending from said cylinder for delivering oil to said gear mechanism and operating connections.
15. A pump comprising a base, a casing mounted thereon, planetary gear mechanism in said casing, a crank pin connected to said planetary gear mechanism and reciprocable thereby in a straight line, a plurality of pump rods offset with relation to said gear mechanism, a corresponding number of stuffing boxes thereon and through which said pump rods pass, and operating connections between said crank pin and said pump rods for reciprocating the latter in a plane parallel to the plane of motion of said crank pin.

16. A pump comprising a base, a casing mounted thereon, planetary gear mechanism in said casing, a crank pin connected to said planetary gear mechanism and reciprocable thereby in a straight line, an oil reservoir below said mechanism, a plurality of pump rods offset with relation to said gear mechanism and oil reservoir, a corresponding number of stuffing boxes above and outside the limits of said oil reservoir, said pump rods passing through said stuffing boxes, and operating connections between said crank pin and said pump rods for reciprocating the latter in a plane parallel to the plane of motion of said crank pin. 70
17. A pump comprising a base, a casing mounted thereon, planetary gear mechanism in said casing, a crank pin connected to said planetary gear mechanism and reciprocable thereby in a straight line, an oil reservoir below said gear mechanism, an inwardly concaved partition which constitutes one of the confining walls of said oil reservoir, a plurality of pump rods passing through the space provided by said concaved partition, and operating connections between said crank pin and said pump rods for reciprocating the latter. 80
18. A pump comprising a base, a casing mounted thereon, planetary gear mechanism in said casing, a crank pin connected to said planetary gear mechanism and reciprocable thereby in a straight line, two concentrically arranged pump rods offset with relation to said gear mechanism, a connection between said crank pin and the inner one of said pump rods for reciprocating the latter in unison therewith, a pair of tie rods connected with the outer pump rod and movable in a common plane with the inner pump rod at opposite sides of the latter, a cross head to which the upper ends of the tie rods are secured, and operating connections between said crank pin and said cross head for reciprocating the latter in the opposite direction relatively to said inner pump rod in a plane parallel to the plane of motion of said crank pin. 90
19. A pump comprising a base, a casing mounted thereon, planetary gear mechanism in said casing, a crank pin connected to said planetary gear mechanism and reciprocable thereby in a straight line, two concentrically arranged pump rods offset with relation to said gear mechanism, a connection between said crank pin and the inner one of said pump rods for reciprocating the latter in unison with the crank pin, a pair of tie rods connected with the outer pump rod and movable in a common plane with the inner pump rod at opposite sides of the latter, stuffing boxes supported by said casing and through which said inner pump rod and said tie rods pass respectively, a cross head to which the upper end of the tie rods are se- 100
- cured, and operating connections between said crank pin and said cross head for reciprocating the latter in opposite direction relatively to said inner pump rod in a plane parallel to the plane of motion of said crank pin. 105
20. A pump comprising a base, a casing adapted to be slid thereon, means for securing said casing in fixed position on said base, planetary gear mechanism in said casing, a crank pin connected to said planetary gear mechanism and reciprocable thereby in a straight line, two concentrically arranged pump rods offset with relation to said gear mechanism, a detachable connection between said crank pin and the inner one of said pump rods for reciprocating the latter in unison with the crank pin, a pair of tie rods connected with the outer pump rod and movable in a common plane with the inner pump rod at opposite sides of the latter, a block detachably secured to said casing, stuffing boxes carried by said block and through which said inner pump rod and said tie rods pass respectively, a cross head to which the upper ends of the tie rods are detachably secured, and operating connections between said crank pin and said cross head for reciprocating the latter in the opposite direction relatively to said inner pump rod in a plane parallel to the plane of motion of said crank pin. 110
21. A pump comprising a base, a casing mounted thereon, planetary gear mechanism in said casing, a crank pin connected to said planetary gear mechanism and reciprocable thereby in a straight line, two concentrically arranged pump rods offset with relation to said gear mechanism, a connecting rod journaled at its lower end on said crank pin for reciprocation thereby, a projection extending laterally from said rod and to which the inner one of said pump rods is attached, an equalizer bar attached to the upper end of said journaled rod, a cross head above said pump rods and to which the outer pump rod is attached, two flexible operating members attached respectively to the ends of said equalizer bar and attached to the upper side of said cross head, and two flexible retriever members connecting the lower side of said cross head with the upper end of said journaled rod. 115
- In testimony whereof I hereunto affix my signature. 120
- EDWARD E. JOHNSON. 125
